UNITED STATES PATENT OFFICE.

ABE J. FREEDMAN, OF CHICAGO, ILLINOIS.

FOLDING CHAIR OR COUCH.

1,334,296.

Specification of Letters Patent. Patented Mar. 23, 1920.

Application filed March 12, 1919. Serial No. 282,120.

To all whom it may concern:

Be it known that I, ABE J. FREEDMAN, a citizen of the United States, residing at Chicago, in the county of Cook and State 5 of Illinois, have invented a new and useful Improvement in Folding Chairs or Couches, of which the following is a specification.

My invention relates to folding chairs or couches and may be considered as an improvement of the construction and arrangement shown in my Patent No. 1,044,160, of November 12th, 1912.

One of the important objects of my invention is to provide a simplified hinge support for the folding bed frame. Another object is to provide improved arrangement for supporting the couch back structure to be raised vertically and held in upward position while the bed frame is folded up 20 and placed at the rear of the couch frame.

On the accompanying drawings, which illustrate my invention—

Figure 1 is a side elevational view of the couch in folded condition, one of its sides 25 being removed.

Fig. 2 is a sectional view on plane 2—2 of Fig. 1 showing the parts in folded up position.

Fig. 3 is a sectional view on plane 3—3 30 of Fig. 1.

Fig. 4 is a side elevational view of the couch when unfolded, the one side of the couch being removed, and

Fig. 5 is a sectional view on the plane 35 5—5 of Fig. 4.

The couch or chair has the side structures or walls 10 and 11 having the vertical back parts 10' and 11' and the legs 12. These side structures are connected together by a 40 suitable seat frame, in this case the box-like structure 13, the bolts 14 securing the side structures to the seat frame. A seat cushion structure 15 rests along its front edge on the front of the seat structure and 45 at its rear end is supported by means of pins 16 engaging in the notches 17 at the upper ends of the supporting plates 18 secured to and extending upwardly from the seat frame.

50 A back frame 19 is of L-shaped cross section and is preferably of metal and supports on its front surface the cushion 20. Secured to the rear wall 21 of the couch adjacent the couch side walls are angle bars 55 22 and 23, to each of which a set of levers 24 and 25 are pivoted. These levers are of

equal length and at their front ends are pivoted to the respective sides of the back frame 19. The levers of each set are parallel and being of equal length, the couch 60 back structure when raised and lowered will always be vertical, that is vertical and parallel with the rear wall 21 of the couch. Connecting between the levers and the angle bars are tension springs 26 which tend to 65 swing the levers upwardly, and which will hold the back structure in its upward position. Pins 27 and 28 removably inserted through the couch side walls extend above the upper levers 24 when the back structure 70 is down, and hold the back structure in such lowered position. Upon releasing the pins the springs 26 will assist in raising the back frame and will hold it in its upward position. 75

When the back structure is raised a suitable passageway is left through which the folded bed frame may be passed when taken out of or folded up into the storage space 29. The bed frame structure comprises front 80 and rear U-shaped sections 30 and 31 bent up of angle iron, the ends of the frames being pivoted to plates 32 to which the intermediate legs 33 are pivoted at their upper ends. At the outer end of the section 30 85 legs 34 are pivoted. At the inner end of the section 31 arms 35 are secured and extend downwardly and are pivoted at their lower ends by means of screws 36 to fittings 37 secured to the side walls 10 and 11 of the 90 couch.

In Fig. 4 the bed frame is shown out and unfolded ready for use. To fold up the frame and to store it within the couch the front section 30 is first swung back against 95 the frame 31 and the legs 34 dropped into parallelism with the sections and then the folded together structure is swung rearwardly around the pivots 36 into upright position within the space 39, the legs 33 100 automatically assuming vertical position. The rear wall of the seat frame 13 has notches 38 cut therein for accommodating the arms 35, the arms resting on the abutments of the notches after the frame has been 105 folded into space 29, the pivot connections of the arms 35 with the seat structure 13 and the rear wall of such seat structure support the folded up bed frame. After the frame has been folded in the space 29 110 the back structure 19 is lowered and the pins 27 and 28 inserted to lock the frame

against raising by the springs 26. When it is desired to use the couch as a bed the pins 27 and 28 are withdrawn and the back structure raised and the bed frame swung out 5 and unfolded. The seat frame 13 can serve as a receptacle for the bed clothes.

The structure can be of single or double width and can be in the form of a chair or couch.

10 Having described my invention, I claim as follows:

In a folding chair or couch, the combination of side walls, a seat structure extending between the side walls, a rear wall, there 15 being storage space between said seat structure and said rear wall, a back structure for

coöperating with said seat structure to form a seat, parallel bars 24 and 25 pivoted to said back structure and said rear wall for permitting vertical movement of said back structure parallel with said rear wall springs 26 connecting between said rear wall and said bars intermediate the bar ends and tending to raise said back structure, and locking pins 28 extendible through the side 25 walls into the paths of the upper bars 24 when the back structure is down to hold the arms and back structure in such position.

In witness whereof I hereunto subscribe my name this 6th day of March, A. D. 1919. 30

ABE J. FREEDMAN.
